BASEBALL GAME APPARATUS

Abe Rose, Chicago, Ill., assignor of one-half to
Sidney J. Eisenberg, Chicago, Ill.

Application November 19, 1949, Serial No. 128,324

6 Claims. (Cl. 273—88)

1

This invention relates to a game in which a ball is propelled outwardly onto a game board having a number of depressed channels and holes adapted to receive the projected ball and bring it to rest, and more particularly to a baseball type game of the character described in which the actual batting procedure and movement of the base runners simulates as far as possible actual play which occurs in baseball.

One of the objects of this invention is to provide a simple device for propelling a ball outwardly onto a game board in any one of a plurality of directions depending upon the way the ball is played by the player and without moving or adjusting any portion of the apparatus.

Another object of this invention is to provide a ball game apparatus which converts the movement of a dropped ball to a movement along the surface of the game board in a direction depending upon the point of contact of the ball with the apparatus.

A further object of this invention is to provide a baseball game in which the score achieved by a player is determined more by skill on the part of the player rather than by mere chance.

A still further object of this invention is to provide a ball game board and ball propelling apparatus that is easily and inexpensively produced.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which—

Figure 1 is a plan view of the baseball game showing a typical arrangement of the elements used in the play of the game.

Figure 2 is a partially broken away isometric view showing a player's fingers holding the ball in playing position above the home plate.

Figure 3 is an enlarged side view of the home plate taken on the view 4—4 of Figure 1.

Figure 4 shows an alternative shape for the home plate and is taken on the same view as Figure 3.

Figure 5 shows an alternative shape for the home plate and is taken on the same view as Figure 3.

Figure 6 shows a side view of the magnet that is used to collect the balls.

Referring to Figure 1 there is shown a playing board generally indicated by the numeral 10. The playing board 10 has a raised border 11 and a flat section 12. Additional raised members 13

2

and 14 cut across two of the corners of the playing board 10 thus setting off these two corners from the field portion 15 of the playing board. Raised members 13 and 14 are substantially at right angles to each other and serve as boundaries to the baseball field 15, raised member 13 lying along the 1st base side of the field and raised member 14 lying adjacent the 3rd base portion of the field.

10 The playing field 15 consists of three sections, an infield diamond 16, an outfield section 17, and boundary channel sections 18 surrounding the infield and outfield portions. All three sections of the playing field lie in different planes. The 15 channel sections 18 lie in the same plane and are a part of flat section 12. The outfield section 17 lies in a plane above the plane of channels 18 and the infield diamond 16 lies in a plane above the plane of the outfield 17. This stepwise arrangement of sections can be most clearly seen in Figure 2.

20 Mounted on the home plate region of the infield diamond 16 is a propelling member or home plate 19. As more clearly shown in Figures 3 and 4 this home plate 19 has an upwardly inclined surface 20 which faces outwardly toward the outfield section 17. The home plate 19 has two vertical sides 21 one of which lies along the first base side of the baseball diamond, the other side lying along the third base side of the baseball diamond. The intersection of these two vertical sides 21 is the vertex 22 of the home plate 19. The home plate 19 is a body of revolution whose axis of revolution is the vertex 22. The cross sectional views of the home plate 19, taken upon any vertical plane passing through the vertex 22 formed by the intersection of the vertical side 21, are identical. In fact, any such cross section of the home plate would be the same as the side view as shown in Figure 3. Another way of saying this is that the home plate is a body of revolution that is formed by revolving a surface such as that shown in Figure 3 about a vertical axis, coincident with the vertex 22, through an arc of 90°.

30 The outfield portion 17 is provided with a plurality of holes which are designated with different baseball terms as illustrated in Figure 1. Thus, when a ball stops in a certain hole or enters a channel at a given region, the result of that given play is designated by the baseball term associated with the hole or the channel. The base of these holes is the flat section 12 of the playing board 10.

55 The raised members 13 and 14 at the region adjacent the home plate intersect parallel raised

members 23 and 24 which in turn are perpendicular to the raised border 11. This arrangement provides a ball well 25 which is in communication with the channels 18. The channels 18 are more clearly defined in the region adjacent infield diamond 16 in that they are bounded between the diamond 16 and the raised members 13 and 14.

In playing the game a ball 26, preferably of steel, is held by the player between his thumb and forefinger as shown in Figure 2 above the inclined face 20 of the home plate 19. When the ball 26 is dropped it strikes the inclined surface 20 and is propelled outwardly over the infield diamond to the outfield section 17. The playing board 10 is inclined so that the ball after leaving the home plate is continually traveling up a slope. This inclining of the board can be accomplished by mounting legs under the playing board along the board's outfield edge (the top edge in Figure 2). These legs are not shown in the drawings but it should be obvious that the board can be propped upon almost any object to give it the necessary slope. The purpose of having the playing board inclined is so that if the ball 26 does not fall into any of the holes in the outfield section 17, they will be returned to the ball well 25 where they can be replayed. Thus, as a ball 26 is projected into the outfield it either will enter one of the holes therein or will roll into the channel section 18 where it will be returned to the well 25.

This game is a game of skill, and it will be noted that if the ball 26 does not go out far enough it will roll into a channel section which has the designation—Strike. If the ball is projected outwardly too far it will go into the channel section marked—Out. Furthermore, pins 27 are provided which mark off a portion of the channel 18 as having a value—Ball. The purpose of having the outfield section 17 at a different level than infield diamond 16 is so that the ball is prevented from returning over the diamond portion 16 and must be returned to the channel 18 and thence to the well 25.

It can be seen that the region to which the ball is propelled is a function of the skill of the player in dropping his ball 26 at a suitable point upon the face 20 of the home plate. A plurality of guide lines drawn upon the infield diamond 16 and extending radially from the vertex 22 of the home plate 19 indicate to the player approximately where the ball should be dropped on the face 20 of the home plate so as to direct the ball 26 to the portion of the outfield desired. Furthermore, skill is involved in holding the ball at the correct height in order to obtain the correct amount of propulsion outwardly on to the outfield 17. No moving parts are necessary to enable the player to direct his ball to any region whatsoever in the outfield.

When a ball stops in a certain hole or enters a channel at a given region, the results of that given play are designated by the baseball term associated with the hole or the channel. If a hit is made, the ball should be removed from the hole in which it lies. Then a piece (not shown), designating the runner and having a rod-like mounting finger of a size adapted to fit into the base hole, is put into the appropriately numbered base hole. The basic rules of this game are substantially the same as in an ordinary baseball game and the runners advance in the same manner, such movement being simulated by actually moving the runners from base to base.

In order to record what has occurred on the playing field, a plurality of counting dials 33 are

provided which record the outs, balls, strikes and runs. These counting dials are located in the corners bounded by raised border 11, and raised members 13 and 14, and 23 and 24. These dials 5 can be easily made of a pointed member secured to the board by means of a thumb tack or the like. Also provided in one of the corners is a scoreboard which consists of a raised frame work 28 which is mounted on the flat section 12 of the 10 playing board 10. A number of tabs 29 are provided having printed thereon the names of teams and numbers which tabs may be inserted in the scoreboard to designate the teams playing and to designate the scores that are made in each 15 inning.

The bases to which the runners move may be positioned upon the playing field 15 but in the preferred embodiment are positioned as shown. The first and third bases are located in triangular members 30 which are mounted on flat section 12 and are positioned in the corner between raised border 11 and raised members 13 and 14. Second base is located opposite the home plate in the furthermost portion of the outfield 17 and is set off from the remainder of the outfield 17 by a raised collar 31 which prevents any of the balls from entering the hole which is designated as second base. Since the steel balls are quite small they are relatively difficult to pick 25 out of the holes, and therefore a small permanent magnet 32 (as shown in Figure 6) is provided which is used to pick up the balls on the playing field.

The shape of the upwardly inclined surface 35 20 of the home plate may be varied. Although the preferred embodiment of the home plate shown in Figure 2 has a convexly curved surface, the home plate may also have a concavely curved surface like that shown in Figure 4. The 40 surface 20 may also be flat, as shown in Figure 5 of the drawings.

While there has been shown and described a particular embodiment of this invention, it will be obvious to those skilled in the art that various 45 changes and modifications may be made therein without departing from the invention and, therefore, it is intended in the appended claims to cover all such changes and modifications as fall within the true spirit and scope of the invention.

What I claim as new and desire to secure by Letters Patent of the United States is:

1. A baseball game comprising an inclined playing board, a propelling member for changing the vertical movement of a ball to a movement upwardly along the inclined surface of said playing board, said playing board having a plurality of channels, two of said channels bounding a simulated baseball field comprising a home plate, an infield surface and an outfield surface, said playing board also having therein a plurality of holes, three of said holes serving as the bases of the simulated baseball field, the remainder of said holes being located in the outfield surface of the baseball field and adapted to receive the projected ball, said channels being adapted to receive the projected balls and return them to a region adjacent the home plate, said holes and channels having various designated game values, and said propelling member serving as the home plate of the simulated baseball field, said infield surface lying in one plane, the outfield surface spaced below said infield surface, and the surface of the channels lying below said outfield surface, whereby the pro-

propelled ball is restrained from returning over a surface over which it has passed.

2. A baseball game comprising an inclined playing board, a propelling member for changing the vertical movement of a ball to a movement upwardly along the inclined surface of said playing board, said playing board including a polygonal channel bounding a simulated baseball field comprising a home plate, an infield surface, and an outfield surface, a portion of the channel adjacent the home plate being enlarged to form a collection region, said propelling member serving as the home plate of the simulated baseball field and having an upwardly inclined surface of revolution facing in the direction the ball is to be propelled over the playing board surface, the ends of said inclined surface terminating at the sections of the channel which bound the infield section, said infield surface lying in one plane, the outfield surface being spaced below said infield surface, and the surface of said channel lying below the outfield surface, whereby the propelled ball is restrained from returning over a surface over which it has passed and is directed to the bounding channel, whence it is returned to said collection region adjacent the home plate.

3. A baseball game comprising an inclined playing board, a propelling member for changing the vertical movement of a ball to a movement upwardly along the inclined surface of said playing board, said playing board including a polygonal channel bounding a simulated baseball field comprising a home plate, an infield surface, and an outfield surface, a portion of the channel adjacent the home plate being enlarged to form a collection region, said propelling member serving as the home plate of the simulated baseball field and having an upwardly inclined surface of revolution facing in the direction the ball is to be propelled over the playing board

surface, the ends of said inclined surface terminating at the sections of the channel which bound the infield section, said infield surface lying in one plane, the outfield surface being spaced below said infield surface, the surface of said channel lying below the outfield surface, whereby the propelled ball is restrained from returning over a surface over which it has passed and is directed to the bounding channel, whence it is returned to said collection region adjacent the home plate, a plurality of game value designations along the length of the channel, and members, positioned at the edge between said outfield surface and said channel surface and spaced from the edges between said infield surface and said outfield surface, adapted to form regions associated with the various game value designations along the length of the channel.

4. A baseball game as set forth in claim 2 wherein said upwardly inclined surface of revolution of the home plate is convexly curved.

5. A baseball game as set forth in claim 2 wherein said upwardly inclined surface of revolution of the home plate is concavely curved.

6. A baseball game as set forth in claim 2 wherein said upwardly inclined surface of revolution of the home plate is straight along its length.

ABE ROSE.
